UNITED STATES PATENT OFFICE.

JOHN D. MILLER, OF RIVERDALE, MARYLAND, ASSIGNOR OF TWO-THIRDS
TO CHARLES P. THOMSON, OF WASHINGTON, DISTRICT OF COLUMBIA,
AND JULIAN L. WRIGHT, OF COLLEGE PARK, MARYLAND.

PUZZLE.

SPECIFICATION forming part of Letters Patent No. 536,220, dated March 26, 1895.

Application filed July 5, 1894. Serial No. 516,650. (No model.)

To all whom it may concern:

Be it known that I, JOHN D. MILLER, a citizen of the United States, residing at Riverdale, in the county of Prince George's and State of Maryland, have invented certain new and useful Improvements in Puzzles; and I do hereby declare the following to be a full, clear, and exact description of the invention, such as will enable others skilled in the art to which it appertains to make and use the same.

This invention relates to puzzles.

The object of the invention is to produce a compact, neat puzzle of an intricate character, having a spindle upon which are mounted two heads and several rings, each adapted to be revolved independently upon the spindle. Each head is hollowed out, but only one of them is provided with a cap partially covering the hollowed out portion, said cap having a cutaway portion adapted to register with a groove in the spindle and notches formed in the rings. Balls are placed in each head but only those in the capped head enter the grooves and notches referred to. The other balls are simply used as dummies to perplex the operator.

In the drawings: Figure 1 is a side elevation of my invention. Fig. 2 is a central longitudinal section through the same showing the puzzle locked. Fig. 3 is a similar view showing parts in unlocked position. Fig. 4 is a perspective view showing parts separated.

1 represents the spindle provided with the head, 2 a groove or cut out portion 3, and a groove 4 extending entirely around the same; said groove being located at one end of the groove 3.

5 is a head which is bored out at 6 and is provided with an opening 7 through which the spindle passes, the head 2 of said spindle being countersunk in the head 5 as shown.

8 is a disk provided with a sleeve 9, said sleeve being provided with a cutaway portion or groove 10. An opening extends through the center of the disk and sleeve, through which the spindle passes. I shall, for convenience refer to the disk 8 and sleeve 9 as the "sleeved disk."

11 and 12 are two disks, each provided with a cut out portion or notch 13 and 14 respectively.

15 is a head provided with cut out portions 16, 17 and 18; one end of the spindle 1 working in the portion 18, and the balls 19 in the portion 17. In the portion 16 I countersink a cap 20 and secure it in position by any suitable means. This cap is provided with a notch 21.

22 is a covering for the puzzle on which may be printed, (as shown) various letters with which a certain sentence or name of a firm, using the puzzles for purposes of advertising may be formed.

23 are balls loosely confined in the head 5 as dummies.

The parts are put together by first passing one end of the spindle through the opening 7 in the cap 5. Then put the dummy ball 23 in the space 6. This space 6 is of such width that there will be a slight frictional contact between the balls and spindle. The sleeved disk is then slipped over the spindle and disks 11 and 12 slipped over the sleeve 9. The disks, sleeve disk and the spindle are turned until the notch or groove in each, register with each other. I then drop the balls 19 into the cavity thus formed and place the head 15 over the end of the spindle in such a manner that the notch 21 will register with the cavity just mentioned. Holding the cap rigidly in this position, I invert the whole whereby the balls 19 roll through the notch 21 into the cap and by turning the cap it is locked to the spindle. The balls 19 work in the groove 4 on the spindle and have a slight frictional contact with the same. The disks are then turned at random to separate the notches on each.

To open the puzzle it is necessary to turn the spindle, disks and head 15 until the notches in each register with one another. This is very difficult, owing to the fact that the spindle is loose and frictional contact between it and the balls 19, will turn the spindle around with the head 15 without changing its position. Consequently, the notch 21 in the head and the groove 3 in the spindle will not

register. To overcome this frictional contact it is necessary to place the thumb on the head 2 of the spindle to bind it tightly in its countersink, whereby the head 15 may be turned 5 so that the notch will register with the groove 3 in the spindle while the disks may in turn be brought in to proper position so that the balls will drop out of the head 15 into the cavity formed by the grooves or notches 3, 10, 10 13, and 14 and thus unlock the puzzle.

On the outside of the puzzle is pasted a wrapper on which are printed various letters adapted to form sentences or an advertiser's name, &c., which when properly arranged 15 form the key for opening the puzzle, thereby, increasing the intricacy of the puzzle. Business cards, announcements, &c., may be pasted on the end of the puzzle.

What I claim, and desire to secure by Letters Patent, is—

1. A puzzle comprising a spindle having grooves, grooved heads loosely mounted on the same, balls located in the said heads to make frictional contact between the heads and 25 the spindle, and notched or grooved disks

loosely mounted on said spindle between the heads.

2. A puzzle comprising a spindle having grooves, grooved heads loosely mounted on said spindle, balls located in said heads, whereby frictional contact is made between the heads and spindle, a sleeved disk having a notch or groove and loosely mounted on said spindle between the heads, and notched disks loosely mounted on said sleeved disk. 30

3. In a puzzle the combination with a grooved spindle, loosely mounted in a series of notched disks, and a grooved head loosely secured to one end of the spindle, of a head having a groove, a notched cap countersunk 40 in said head and balls located in said groove and held there by the cap, said balls making a frictional contact between the head and the spindle.

In testimony whereof I affix my signature 45 in presence of two witnesses.

JOHN D. MILLER.
